DESIGN.

T. I. RANKIN.
PARLOR STOVE.

No. 18,744.

Patented Nov. 20, 1888.

UNITED STATES PATENT OFFICE.

THOMAS I. RANKIN, OF PHILADELPHIA, PENNSYLVANIA, ASSIGNOR TO
THE ABRAM COX STOVE COMPANY, OF SAME PLACE.

DESIGN FOR A PARLOR-STOVE.

SPECIFICATION forming part of Design No. 18,744, dated November 20, 1888.

Application filed October 8, 1888. Serial No. 257,582. Term of patent 7 years.

To all whom it may concern:

Be it known that I, THOMAS I. RANKIN, a citizen of the United States, and a resident of Philadelphia, Pennsylvania, have invented a new and Original Design for a Parlor Stove, of which the following is a specification.

My design is fully shown in the accompanying print.

Prominent features of the design are the cylindrical body with lower projecting rim, the door frame discontinued some distance from the top of the body, so that the upper portion of said body preserves its true cylindrical form, the fire-pot in the form of an inverted truncated cone, and the base or ash-pit section in the form of a truncated quadrangular pyramid.

Minor features of the design are the dome-top and urn, the door, the fenders, and the feet or legs; but the specific ornamentation of these parts forms no essential part of the design.

I claim—

The design for a parlor stove, substantially as described, and as shown in the accompanying drawing.

In testimony whereof I have signed my name to this specification in the presence of two subscribing witnesses.

THOS. I. RANKIN.

Witnesses:

WILLIAM D. CONNER,
HARRY SMITH.
